CLAIM

The ornamental design for a bubble wand, as shown and described.

DESCRIPTION

FIG. 1 is a top perspective view of bubble wand, showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front view of the bubble wand, shown in an in use configuration.

The broken lines in the drawings depict portions of the bubble wand, that form no part of the claimed design.
